UNITED STATES PATENT OFFICE.

JOHN L. MOHUN, OF BROOKLYN, NEW YORK.

CAR-ROOF.

1,155,604.

Specification of Letters Patent.

Patented Oct. 5, 1915.

Application filed December 19, 1912. Serial No. 737,668.

To all whom it may concern:

Be it known that I, JOHN L. MOHUN, a citizen of the United States, residing at Brooklyn, in the county of Kings and State 5 of New York, have invented a certain new and useful Improvement in Car-Roofs, of which improvement the following is a specification.

This invention relates to car roofs, and 10 more particularly to metal roofs for freight cars, one of the objects being to provide an improved overlapping joint between the adjacent edges of the metal roofing sheets, which will effectually drain off the water at 15 the sides of the car and prevent the admission of rain or moisture through the joint into the interior of the car.

Another object is to provide an improved fastening means or clip device for holding 20 down the roofing sheets at the sides and ends of the car.

In the accompanying drawings: Figure 1 is a transverse section of a side plate and portion of car roof showing the improved 25 clip and fastening means; Fig. 2, a side elevation of same; Fig. 3, a corresponding sectional view of the end plate and clip for holding down the edge of the roofing sheet at the end of the car; Fig. 4, an end elevation of the same; Fig. 5, a transverse section of an overlapping joint of the adjacent edges 30 of the metal roofing sheets taken at the car ridge and showing the running board saddle; Fig. 6, a similar section of the joint at 35 a point nearer the eaves of the car; Fig. 7, a transverse section of a portion of the car roof taken through the joint between adjacent roofing sheets; and Figs. 8, 9 and 10, detail views showing modified forms of 40 overlapping joints of the metal roofing sheets.

According to the construction shown in 45 Figs. 1 and 2, the improved fastening or clip for holding the roofing sheet, 11, upon the side plate, 12, comprises a casting, 13, having a projection, 14, extending over the roofing sheet and side plate, and also provided with a flange or socket, 15, projecting from its inner side within a recess formed 50 in the fascia, 16, on which the clip is mounted, the socket engaging the head of a bolt, 17, passing through the fascia and side plate for securely fastening the clip and fascia in position. It will be understood that the 55 socket flange is open on one side at least for

inserting the bolt head into the socket before applying the clip to the fascia. The fascia is preferably secured to the side plate below the top thereof, and the end of the roofing sheet may be bent down over the side 60 plate and extend over the upper inclined face of the fascia, there being a sufficient clearance between the downturned flange of the roofing sheet and the side of the frame or plate to give the desired flexibility of 65 the roof. The clip is also set away from the side plate and roofing sheet at this point in order to permit the sheet to move relative to the frame of the car.

By using the socket flanges, 15, sunk into 70 the fascia, the outer face of the clip may be smooth and unbroken so that there is no chance for the entrance of moisture through the clip to the space around the bolt head or bolt in the fascia, and as the clip is also 75 set in flush with the outer line of the fascia, all the connecting parts are within the usual clearance lines as determined by the fascias at the sides of the car.

For the purpose of preventing any water 80 from draining down over the fascia to the inside face of the clip, the extreme lower end of the roof sheet may be bent up at this point in the form of a deflecting flange, 18, to divert the drainage water to either side of 85 the clip, thereby excluding all moisture from the joint around the bolt head socket within the fascia. The clip may be provided with a depression, 19, for engaging the roofing sheet joint above the fascia to assist in holding 90 the roofing sheet in position. This improved clip construction may also be employed upon the fascia at the end of the car where it is secured to the end frame or plate, 95 12^a, as shown in Figs. 3 and 4, of the drawings.

In case the roofing sheet does not lie close to the frame plate at the point where it is desired to fasten the clip, a depression may be formed in the roofing sheet at this position, as shown in Figs. 1 and 2, and such depression may be of any desired length, or extend all the way to the car ridge, if preferred. The clip may also be provided with a flange, 20, extending down upon the sheathing and fastened with a bolt, 21, if desired.

According to another feature of my improvement, the roofing sheets are designed 110 to have overlapping side edges extending

transversely of the car roof, one edge being formed with a drain trough, 22, and the contiguous edge of the adjacent sheet being formed to extend over said trough and constitute a cover or cap section, 23, therefor, as shown in Figs. 5 to 10, of the drawings. With this construction, the several roofing sheets are preferably, but not necessarily, designed to extend the full width of the car 10 from eaves to eaves, and in such case, the running board saddle, 24, may be mounted directly upon the cap section, 23, at the ridge and secured thereto by one or more bolts, 25, as shown in Fig. 5. The bolts being located over the trough section, 22, any leakage of water through the cap sections at the bolt holes will readily drain down through the trough and over the eaves of the car.

20 If preferred, the trough portions may be flared out and made shallower from the ridge toward the eaves, as indicated by the sections shown in Figs. 6 and 8. The trough and cap sections may be formed in a variety 25 of ways in the adjacent edges of the roof sheets. As shown in Figs. 5 and 6, the edge having the trough, 22, is also provided with a shallow depression, 26, into which the extreme side edge of the cap sheet is turned 30 and flanged as indicated at 27, while another depression, 28, may be formed at the edge of the trough sheet, above which there is a slight downwardly projecting rib, 29, formed in the cover sheet.

35 According to the construction shown in Figs. 8, 9 and 10, the bottom of the trough section is in substantially the same plane with the body portion of the sheet, and is formed by a vertical rib, 30, spaced from the 40 turned up edge, 31, which also has a substantially horizontal flange, 32, at its upper end, while the cap portion is formed by bending the same upward into a substantially rectangular section over the trough 45 and forming a flange, 33, to bear upon the roofing sheet beyond the rib, 30. The top portion of the cap may also be provided with a depression, 34, if desired, for assisting to deflect any water which might 50 possibly pass over the rib, 30, downward into the trough.

It will now be seen that with any of these improved forms of joints between adjacent roofing sheets, any water which may be 55 driven into the joint will be effectually drained off at the eaves without permitting access of moisture to the interior of the car, and the trough and cap portions will always occupy their proper positions, while 60 at the same time, dispensing with the use of

additional and separate parts for this purpose.

Having now described my invention, what I claim as new and desire to secure by Letters Patent is:—

1. In a car roof, the combination of metal roofing sheets with overlapping edges located transversely of the car, one of said edges being shaped to form a drain trough and the other edge extending over and constituting a cover for said trough, a running board saddle, and fastening bolts therefor extending through and bolted to said cover portion over said trough.

2. A car roof, the combination with a frame member, and a fascia having an inclined surface below the top of said frame member, of a metal roofing sheet supported on said frame and having its end turned down over the inclined surface of the fascia, and a metal clip fastened to the fascia and having projections for holding the metal sheet down upon the frame member and upon the fascia.

3. In a car roof, the combination with a frame member and a fascia, of a metal roofing sheet supported on said member, a metal clip mounted on said fascia and extending over said roofing sheet, said clip also having a socket on its inner face projecting into a recess in said fascia, and a bolt having a head located in said socket and extending through the fascia and the frame member.

4. In a car roof, the combination with a frame member and a fascia, of a roofing sheet having its end turned down over the frame and extending over the fascia, and a metal clip fastened to the fascia and extending over the roofing sheet for holding the same in position, the end of said sheet upon the fascia being turned up to form a deflecting flange beneath the clip.

5. In a car roof, the combination with a frame member and a fascia, of a roofing sheet having its end turned down over the frame and extending over the fascia, a metal clip mounted on said fascia and extending over the roofing sheet, and a bolt connected to the inside of the clip for fastening the same to the fascia and frame member, the end of the roofing sheet upon the fascia being turned up to form a deflecting flange beneath the clip.

In testimony whereof I have hereunto set my hand.

JOHN L. MOHUN.
